Patented June 17, 1902.

R. H. WAPPLER.
ELECTROSURGICAL INSTRUMENT.

(Application filed June 10, 1901.)

(No Model.)

UNITED STATES PATENT OFFICE.

REINHOLD H. WAPPLER, OF NEW YORK, N. Y.

ELECTROSURGICAL INSTRUMENT.

SPECIFICATION forming part of Letters Patent No. 702,752, dated June 17, 1902.

Application filed June 10, 1901. Serial No. 63,842. (No model.)

To all whom it may concern:

Be it known that I, REINHOLD H. WAPPLER, a citizen of the United States, residing in the borough of Manhattan, city, county, and State 5 of New York, have invented an Improvement in Electrosurgical Instruments, of which the following is a specification.

My present invention relates to electrosurgical instruments, and particularly to such 10 instruments as are used in diagnosing and treating urinary and gastric diseases. In carrying out my invention I employ two tubes of metal, the one within the other, with the tubes connected and the spaces between the 15 same at the ends thereof sealed and with an insulated conductor lengthwise between the tubes and means for sealing the tubes at the respective ends of the electrical conductor and providing for contact therewith of elec- 20 trical devices. I prefer to place the tubes eccentric and to employ an incandescent electric lamp at one end. The inner tube is open- 25 ended and the forward end cut at an angle. I employ novel terminals for the insulated conductor, which are sealed in an especial manner. I provide removable and inter- 30 changeable tubes adapted to be passed within the aforesaid tubes and used for the purpose of cleansing and examining the interior parts or organ affected, all of which, includ- 35 ing the details of the construction, are hereinafter more particularly set forth.

In the drawings, Figure 1 is a longitudinal section of my improved instrument. Fig. 2 35 is a cross-section on line $x-x$, Fig. 1. Fig. 3 is a cross-section on line $y-y$, Fig. 1. Fig. 4 is an outside view of a removable telescopic tube adapted to fit within the instrument and to be employed for examinational purposes. 40 Fig. 5 is a longitudinal section of a removable part which fits within the instrument and is used for cleansing purposes. Figs. 6 and 7 are elevations and partial sections embodying modifications of my invention.

Referring to Fig. 1, a represents a tube, of 45 metal or other suitable material, and b a smaller tube, of similar material, placed within the tube a and eccentric thereto (see Fig. 3) and open-ended. These tubes may be 50 secured together in any desired manner, and while preferably straight and secured along or at their contacting surfaces they may be

of any configuration adapted to suit the requirements of a particular use. The spaces between the tubes at their respective ends 55 are permanently and hermetically closed by solder.

The tubular end a' is secured to the outside tube a , is preferably of reduced radius, and is offset from the axial line of the tube. 60 The under side of the junction or ends of these tubes a and b is cut away at an angle, as at 2. The space in the open end of the offset tube a' may be filled with an insulating material c —such, for instance, as gutta-percha. 65 The end of the portion a' of the tubes is externally threaded at 3 and adapted to receive the base of a small incandescent electric lamp d or other device. The end cap e is provided with an aperture 4 and interior glass tube 5, cemented thereto, and the same fits over the electric lamp and screws onto the end 3 of the offset portion a' of the tube a , the lamp being employed to illuminate the interior part to be examined. The other end of the tube a is provided with 75 an enlarged tubular portion or sleeve f , which may be integral therewith or otherwise and having a shoulder 6 and threaded exterior 7. The interior of the sleeve f is preferably of appreciably greater diameter than the tube 80 a , thus leaving an annular recess 8 between the parts. The lamp-terminals comprise a ring g , which screws on the sleeve f and abuts against the shoulder 6 and is provided with an annular semicircular groove. The other 85 contact-ring h , whose inside diameter is greater than the outside diameter of the threaded sleeve f , is also provided with an annular semicircular groove and is held in position by a lock-nut i , being insulated therefrom and also from the ring g by washers 90 31. The ring h is flaring and the ring g and lock-nut i are undercut at their opposing edges, so as to exert a wedging action between the parts and hold the ring h in position. 95

Electrical connections are made from the ring h to one terminal of the lamp, preferably by means of a metal strip 9, which is advantageously wound with tape or covered with other insulating material and passed between 100 the tubes a and b , both ends of which are insulated from the tube b . An insulating-ring k and outer contacting metal ring m surround the inner tube b , and one end of the

conductor 9 is secured to the ring *m*, and a pin 10, which passes freely through a hole in the sleeve *f* and is secured in the ring *h*, bears upon the ring *m*. The other end of the conductor 9 passes through the insulating material *c* and is contacted with by one terminal of the lamp. The return-circuit is made through the body of the instrument to the ring *g*. The outer end of the recess 8 is plugged, preferably by an annulus of metal 11, which, together with the soldered joint *c'* at the opposite end, hermetically seal up the space between the tubes and make the same even water-tight.

15 The instrument may be provided with an end eye-shield *l*, adapted to screw on over the sleeve *f* and used for the purpose of facilitating sight through the instrument. The annular semicircular grooves in the rings *h* and *g* are adapted to receive the spring-contacts 12 and 13 of an electric switch 14. (See Fig. 2.) A switch especially applicable for this purpose is shown and described in Letters Patent No. 656,870, granted to me August 28, 25 1900.

In Fig. 4 I have shown a telescopic tube *n*, provided with suitable lenses and an end eye-shield *l'* and adapted to be passed through the inner tube *b*. After the instrument has 30 been inserted for the detection of disease the telescopic tube *n* may be employed for the better inspection of the interior parts, the said tube being of such length that its end may be passed beyond the tapered opening at the 35 end of the instrument. For washing the interior walls of the bladder or other affected organ I provide a tube 15, within which are two smaller tubes 16 and 17, as shown in section in Fig. 5. The smaller tubes are 40 arranged as a supply and return for the cleansing fluid. The orifice 18 of the supply-tube 16 is preferably in the end of the tube 15, which end is made to conform to the shape of the end of the tubes *a* and *b* of the instrument. 45 The intake 19 of the return-tube 17 is preferably in the side of the tube 15 near the end thereof and on top in reference to the tapering portion. The other end of the return-tube 17 is preferably somewhat longer than 50 that of the supply-tube, these ends being adapted to receive rubber tubes or other means for conveying the fluid. The tube 15 is just long enough to pass within the tube *b* and is preferably of such a length that when 55 the collar 20 on tube 15 abuts against the end of tube *b* the tapered end of tube 15 coincides with the tapered ends of tubes *a* and *b*. Thus the open end of the tube *b* is filled up and the insertion of the instrument facilitated. 60 The object of having the return-tube 17, as shown and described, with the intake in the side and the end longer than the supply-tube is because by knowing the position of the instrument the ends of the tubes 15 and *b* may 65 not only be made to coincide exactly, but be so maintained while the instrument is being inserted in the body, so as not to cause any

injury during insertion or to the organ being treated. After the tubes are in this position it is evident that the interior one, 15, 70 must be turned through at least ninety degrees before the cleansing apparatus may be used.

In the modification shown in Fig. 6 the electric-light end of the instrument is offset so 75 that the axial line thereof is parallel to that of the main portion of the instrument. In this construction the electric-light bulb *d'* is preferably secured directly within the end cap *e'*, and the base of the lamp screws in the 80 end of the offset portion. In Fig. 6 I have also shown a modified terminal for the electrical connections leading to the lamp. The tube *a* in this instance is provided with a branch 21, which latter is filled with an insulating material 22, and a dome-like cap 23 is adapted to screw on or otherwise be secured to the branch 21. The cap 23 is partially filled with insulating material, in the center of which is a terminal 24, to which a 85 lead-wire 25 is connected. When the cap 23 is in place, the terminal 24 contacts with a terminal 26 in the insulating material 22, the terminal 26 being electrically connected to the platinum strip or conductor, which leads 90 to the lamp, the return-circuit being made through the body of the instrument to the second lead-wire 27, connected directly to the cap 23.

It is sometimes necessary to examine the 100 lower side walls of an interior affected organ, and to make this possible the instrument may be provided with an opening 28 in the tube *a* (see Fig. 7) opposite to the open end of the tube *b* and a prism 29 secured to the end of 105 the telescope-tube *n* in a modified telescopic instrument. The instruments Figs. 1 and 7 are especially adapted for use with the organs of the male, while the instrument Fig. 6 is especially adapted for use with the organs of 110 the female. The instrument Figs. 1, 4, and 5 is adapted for treatment and examination of stomach troubles, and the instruments Figs. 4 and 5 are adapted for use with the devices Figs. 1, 6, and 7. In this modification the light of the lamp *d* shines in a direction to reflect the image through the prism and lens to the eye of the observer.

I claim as my invention—

1. In an electrosurgical instrument and in 120 combination, two eccentrically-placed inner and outer tubes connected at their contacting surfaces, means for closing the spaces between the same at their respective ends, an insulated conductor longitudinally of the 125 tubes in the space between the same, and means for sealing the tubes at the respective ends of the electrical conductor and providing for contact therewith of electrical devices, substantially as specified.

2. In an electrosurgical instrument and in 130 combination, two eccentrically-placed inner and outer tubes connected at their contacting surfaces, means for closing the spaces be-

- tween the same at their respective ends, an insulated conductor longitudinally of the tubes in the space between the same, and means for connecting to one end of said tubes 5 an electric lamp and means connected to the other end of said tubes for attachment thereto of electric terminals, substantially as set forth.
3. In an electrosurgical instrument and in combination, two eccentrically-placed inner and outer tubes connected at their contacting surfaces so that the inner tube is open-ended, means for closing the spaces between the same at their respective ends, an insulated conductor longitudinally of the tubes in the space between the same, and means for sealing the tubes at the respective ends of the electrical conductor and providing for contact therewith of electrical devices, and a device 10 vice adapted to be inserted through the open-ended inner tube for complementing the functions of the instrument, substantially as set forth.
4. In an electrosurgical instrument, and in combination, two tubes placed the one within the other and connected together, means for closing the space between the same at their respective ends, an insulated conductor longitudinally of the tubes in the space between the same and means for sealing the tubes at the respective ends of the electrical conductor and providing for contact therewith of electrical devices, substantially as specified.
5. In an electrosurgical instrument, the combination with two eccentrically-placed tubes secured together at their contacting surfaces and having the open space between the same at the ends thereof sealed, of an electric lamp secured in an offset position at one end of said tubes, terminals secured to the other end of said tubes, electrical connections between one of said terminals and one of the lamp-terminals, and means contacting with the said terminals for opening and closing the circuit 45 through the lamp, substantially as set forth.
6. In an electrosurgical instrument and in combination, two tubes placed the one within the other and connected together, means for closing the space between the same at their respective ends, an insulated conductor longitudinally of the tubes in the space between the same and means for connecting to one end of said tubes an electric lamp, and means connected to the other end of said tubes for attachment thereto of electric terminals, substantially as specified.
7. In an electrosurgical instrument the combination with two eccentric tubes secured together, having one end cut at an angle and the open space between the tubes at both ends sealed, of an electric lamp in an offset position secured to the tubes at the end thereof cut at an angle, electrical terminals at the other end of the said tubes, a switch having 60 spring-contacts adapted to bear upon said terminals, electrical connections between the said tubes from the said terminals to the said lamp, and a device adapted to be inserted through the open-ended inner tube for complementing the functions of the instrument, substantially as specified.
8. In an electrosurgical instrument, the combination with two eccentric tubes secured together having one end cut at an angle and the open space between the tubes at both ends sealed, of an electric lamp in an offset position secured to the tubes at the end thereof cut at an angle, electrical terminals at the other end of the said tubes, a switch having 65 spring-contacts adapted to bear upon said terminals, and electrical connections between the said tubes from the said terminals to the said lamp, substantially as specified.
9. In an electrosurgical instrument, the combination with two eccentric tubes secured together, having one end cut at an angle and the open space between the tubes at both ends sealed, of an electric lamp in an offset position secured to the tubes at the end thereof cut at an angle, electrical terminals at the other end of the said tubes, a switch having 70 spring-contacts adapted to bear upon said terminals, electrical connections between the said tubes from the said terminals to the said lamp, and a tube fitting the inner of the aforesaid tubes and occupying such position during the insertion of the instrument and having one end made to conform to the eccentric tubes which are cut at an angle, the said tube being provided with independent ducts which 75 are employed as a supply and return for the fluid used for cleansing purposes, substantially as specified.
10. In an electrosurgical instrument, the combination with a pair of tubes one within the other, an insulated conductor longitudinally of the tubes in the space between the same, means for closing the space between the tubes at their respective ends, a sleeve of greater diameter than the outer tube surrounding the same at one end and contacting with the closing device at the said end, and exteriorly threaded, and devices surrounding the said sleeve and in part insulated therefrom and which devices form electrical contacts with the outer tube and with the inner insulated conductor respectively and are adapted for connection with external electric conductors, substantially as set forth.
11. In an electrosurgical instrument, the combination with two eccentrically-placed inner and outer tubes connected at their contacting surfaces with the inner tube at one end longer than the outer tube, of means for closing the spaces between the tubes at one end, a sleeve surrounding the outer tube at its end and of greater diameter exteriorly threaded and extending to the end of the inner tube, an annulus between the sleeve and the inner tube secured thereto for closing 110 this end of the eccentrically-placed tubes, an insulated conductor longitudinally of the tubes in the space between the same and having a terminal within the sleeve, devices sur-

rounding the said sleeve and insulated from one another and through which metallic contacts are formed with the sleeve and with the end of the insulated conductor within the 5 sleeve and which devices are adapted for contact with external electrical devices, substantially as set forth.

12. In an electrosurgical instrument, the combination with two eccentrically-placed inner and outer tubes connected at their contacting surfaces with the inner tube at one end longer than the outer tube, of means for closing the spaces between the tubes at one end, a sleeve surrounding the outer tube at 15 its end and of greater diameter exteriorly threaded and extending to the end of the inner tube, an annulus between the sleeve and the inner tube secured thereto for closing this end of the eccentrically-placed tubes, an insulated conductor longitudinally of the tubes in the space between the same, an insulating-ring and an outer metal ring surrounding the inner tube with one end of the said conductor connected to said metal ring, a series of rings 25 insulated from one another and surrounding the said sleeve, one of said rings being in metallic contact with the sleeve and another of said rings in metallic contact with the end of the insulated conductor within the sleeve and 30 said rings adapted for connection with outside electrical devices, substantially as set forth.

13. In an electrosurgical instrument, the combination with two eccentrically-placed inner and outer tubes connected at their contacting surfaces with the inner tube at one end longer than the outer tube, of means for closing the spaces between the tubes at one end, a sleeve surrounding the outer tube at 35 its end and of greater diameter exteriorly threaded and extending to the end of the inner tube, an annulus between the sleeve and the inner tube secured thereto for closing this end of the eccentrically-placed tubes, an insulated conductor longitudinally of the tubes in the space between the same, an insulating-ring and an outer metal ring surrounding the inner tube with one end of the said conductor connected to said metal ring, a ring *g* 40 surrounding and screwing upon the sleeve *f*, a ring *h* larger than the sleeve surrounding the same and a lock-nut *i* also screwing upon the sleeve with the ring *h* between and insulated from the lock-nut, and the ring *g*, a pin passing through the ring *h* and freely through a hole in the sleeve and contacting forcefully with the ring to which the insulated conductor is connected, the ring *h* being flaring in cross-section and the opposing edges of the 45 ring *g* and the lock-nut *i* being undercut, so that the insulating-washers are at an inclination, the said parts exerting a wedge-like action to hold the ring *h* in position, the rings *h* and *g* having annular semicircular grooves 50 adapted for connection with external electrical devices, substantially as set forth.

14. In an electrosurgical instrument, the combination with two eccentrically-placed inner and outer tubes connected at their contacting surfaces with the inner tube at one end longer than the outer tube, of means for closing the spaces between the tubes at one end, a sleeve surrounding the outer tube at 55 its end and of greater diameter exteriorly threaded and extending to the end of the inner tube, an annulus between the sleeve and the inner tube secured thereto for closing this end of the eccentrically-placed tubes, an insulated conductor longitudinally of the tubes in the space between the same, an insulating-ring and an outer metal ring surrounding the inner tube with one end of the said conductor connected to said metal ring, a ring *g* 60 surrounding and screwing upon the sleeve *f*, a ring *h* larger than the sleeve surrounding the same and a lock-nut *i* also screwing upon the sleeve with the ring *h* between and insulated from the lock-nut, and the ring *g*, a pin passing through the ring *h* and freely through a hole in the sleeve and contacting forcefully with the ring to which the insulated conductor is connected, the ring *h* being flaring in cross-section and the opposing edges of the 65 ring *g* and the lock-nut *i* being undercut, so that the insulating-washers are at an inclination, the said parts exerting a wedge-like action to hold the ring *h* in position, the rings *h* and *g* having annular semicircular grooves 70 adapted for connection with external electrical devices, substantially as set forth.

15. In an electrosurgical instrument and in combination, a pair of tubes one within the other, an insulated conductor longitudinally 75 of the tubes in the space between the same, means for closing the space between the tubes at their respective ends, means for sealing the tubes at the respective ends of the insulated electrical conductor, means for connecting to one end of said tubes an electric lamp in an offset position, and electric connections therefrom to one end of the insulated conductor, lead-wires and terminals from a source of electric energy, an insulated 80 terminal connected to the other end of the insulated conductor, means for covering the latter insulated terminal and to which means one lead-wire is electrically connected and insulated devices electrically connecting the 85 other lead-wire with the insulated terminal, substantially as set forth.

Signed by me this 5th day of June, 1901.
